UNITED STATES PATENT OFFICE

THOMAS H. SYMINGTON, OF BALTIMORE, MARYLAND, ASSIGNOR, BY MESNE ASSIGNMENTS, TO T. H. SYMINGTON AND SON, INC., OF BALTIMORE, MARYLAND, A CORPORATION OF MARYLAND

BOLSTER WITH LATERAL MOTION DEVICES

Application filed April 9, 1926. Serial No. 100,944.

The invention relates to car truck and body bolsters.

The principal object of the invention, generally stated, is to provide a combination of truck and body bolsters equipped with side bearings for sustaining the load and further equipped with means permitting lateral motion of the body bolster with respect to the truck side frames.

10 It is well known that when a freight car is rounding a curve at usual speeds there is an increase in the weight coming upon the inside rail and a tendency for the body to move inwardly with respect to the trucks. On straight track it is known that a car develops a rolling tendency which may be the result of unevenness in the rails or which may arise from other causes. When the rolling tendency synchronizes with the passage of the 15 wheels over the rail joints, as occurs at certain speeds, a pendulum-like action is set up and this is of course highly dangerous on account of the possibility of derailment. This is particularly true in car construction where 20 the weight is sustained by the center bearings with clearance between the side bearing elements on the truck and body bolsters.

It is with the above facts in view that I have 25 designed the present invention which has for an important object the provision of means acting automatically upon the occurrence of side surge for creating an upward thrust upon the truck side bearings for counteracting the added strain thereon and producing a useful 30 force tending to right the car and check or eliminate the rolling tendency.

Another object of the invention is to provide 35 a bearing structure embodying rollers permitting swinging movement of the body bolster with respect to the truck bolster in addition to the means permitting lateral motion of the body bolster with respect to the side frames, these features cooperating not only to retard or check car roll but also to provide 40 greater desirable flexibility under travel conditions.

Another object of the invention is to provide 45 a side bearing structure including a pocket-like bearing member adapted to be mounted in the body bolster for cooperation

with a desired number of rollers operating upon the uppermost bearing element of the side bearing structure carried by the truck bolster, it being a feature to have the pocket or bearing member in the body bolster replace 55 the usual bottom cover plate at this point.

The invention further contemplates the employment of lateral motion rollers of different types or shapes but all arranged to provide the automatic lifting action when side surge 60 of the car body occurs.

To the attainment of the foregoing and other objects and advantages, such as will hereinafter appear, the invention preferably consists in the construction, arrangement and combination of parts to be more fully described and claimed, and illustrated in the accompanying drawings in which:

Figure 1 is a vertical longitudinal section taken centrally through a body bolster and the truck bolster equipped with the side bearing arrangement,

Figure 2 is a vertical cross sectional view taken on the line 2—2 of Figure 1,

Figure 3 is a fragmentary view on a larger scale showing the same roller arrangement and coacting surfaces illustrated in Figure 1, and

Figures 4, 5 and 6 are fragmentary views illustrating different types of rollers and coacting bearing elements or surfaces.

Referring more particularly to the drawings, the numeral 1 designates a truck bolster which, in accordance with the present invention, is formed near each end with a pocket 2 defined between wall members or portions 3 which are shown as extending upwardly beyond the top of the bolster and braced or reinforced by webs 4. The bottom of the pocket is preferably open, as indicated at 5, to permit the escape of water, dirt or other foreign matter which might enter the pocket. The bolster itself is of the usual hollow construction and may be provided with any preferred arrangement of webs 6 for insuring the proper rigidity. Outwardly of the pocket the bolster has an extension 7 received within the side frame in the usual manner and supported by the truck springs, not shown. At the center of the bolster may be 100

provided the usual pin 8 surrounded by an upstanding flange 9 which may be of somewhat elongated shape, for a purpose to be explained, or which could, conceivably, be merely circular.

The pocket 2 is for the accommodation of the side bearing structure which includes a supporting member or bearing element 10 constituting a rest or seat for a preferably 10 frusto-conical roller 11. The top surface of the member 10 is preferably inclined so as to conform to the inclination of the roller and the central portion of this top surface may be recessed or sunk to define upstanding flanges 12 between which the roller is received. The side bearing structure further includes an upper support or bearing element 13 which has its lower surface preferably inclined to correspond to the inclination or 15 pitch of the roller, this undersurface being preferably sunk or recessed at its central portion to define flanges 14 located outwardly of the ends of the roller for maintaining the same in proper relation to the other parts.

20 The end portions of the members 13 depend therefrom and extend into the pocket, that is to say they are located inwardly of the upstanding walls which form the ends of the pocket.

25 It may be desirable to provide a bank or banks of plate or leaf springs 15 located beneath the bearing element or support 10, the springs resting at their ends upon the bottom of the pocket 2, this bottom being preferably concaved as indicated at 16 so as to permit the springs to yield downwardly under pressure. It is likewise preferable that the bottom surface 17 of the member 10 be convex so as to have the proper action upon 30 the springs. Clearly, these springs may be omitted, if desired, in which event the pocket 2 may be made shallower.

35 The numeral 18 designates the body bolster which is provided at the center of its bottom with a center plate 19 located within the confines of the flange 9 but of less size than the space within the flange so that the body bolster will be capable of movement longitudinally of the truck bolster or laterally 40 with respect to the side frames. The center plate 19 is represented as having a socket 20 accommodating the pin 8 but of greater diameter to permit play. Ordinarily, body bolsters of this type are equipped with bottom 45 plates 18^a.

50 Carried by each end portion of the body bolster and located therewithin is a pocket or bearing member 21 here shown as of hollow formation reinforced by webs 22 and 55 provided with flanges or attaching portions 23 located beneath and underlapping the plates 18^a and suitably secured to the horizontal flanges of the channel pressings 24 of which the body bolster is constructed, the body bolster of course including the usual

cover or top plate 25 which is likewise secured to the members 24.

The lateral motion mechanism includes a plurality of rollers 26 located between the bearing member 13 and the pocket or bearing member 21, it being obvious that a plurality of the rollers is preferable in that the strain thereon will be divided. It is of course conceivable that the confronting faces of the members 13 and 21 engaged by the rollers may be of different shapes and in Figures 1 and 3 I have disclosed these confronting surfaces as provided with cam-like curved areas 27 and 28 respectively of similar shape but oppositely arranged so that when the body bolster moves laterally with respect to the truck bolster under the influence of side surge or sway the rollers coacting with the surfaces will act to restore the body bolster to its initial or neutral position subsequent to movement. Furthermore, it is clear that the coaction of the curved surfaces of the rollers will operate normally to maintain the parts in neutral position and oppose relative movement in either direction. They thus perform the twofold function of acting as movement restraining means and recentering means.

55 Instead of providing the simple arcuate surfaces disclosed in Figures 1 and 3 the members 13 and 21 may have their confronting surfaces formed with projections 29 and 30 respectively adjacent which are curved areas 31 and 32 oppositely arranged and coacting with the rollers in identically the same manner as above described.

60 As an alternative construction, the adjacent surfaces of the members 13 and 21 may be flat or plane as indicated at 33 and 34 respectively, in which event rollers 35 of elliptical form may be employed, as shown in Figure 5. It is likewise true that rollers 36 of still a different form may be used as shown in Figure 6, these rollers being of compound curved shape in cross section. The rollers 35 and 36 might be more properly termed rockers on account of their shape and it is clear that they will operate as movement restraining means and also centering means after relative movement of the bolsters in the 65 same manner as the cylindrical rollers 26 coacting with the curved surfaces on the members 13 and 21. It is also conceivable that other arrangements may be resorted to but the foregoing should be sufficient to give 70 full disclosure of the principles involved.

75 Body and truck bolsters constructed, combined and arranged in the manner described and illustrated will possess the great advantage of reducing end thrusts on the side frames and wear and strain on the brasses, journals and car wheels while, furthermore, reducing train resistance on curves as the center line of a train of cars may be permitted to fall inside of the center line of the 80

track. Starting is also facilitated and all strains, stresses and wear reduced in a well recognized manner.

While I have shown and described the preferred embodiment of the invention, it should be understood that the disclosure is merely an exemplification of the principle involved, inasmuch as I reserve the right to make all such changes and modifications in the details of construction and the arrangement and combination of parts to widen the field of utility and increase the adaptability of the invention, or to meet different conditions which may exist, provided such variations constitute no departure from the spirit of the invention or the scope of the claims hereunto appended.

Having thus described the invention, I claim:

1. In combination, a truck bolster having a pocket therein, a side bearing structure mounted in the pocket, a radial bearing member supported by said side bearing structure, a body bolster, a pocket-like bearing member mounted in the body bolster and having a bearing surface above the bottom of the body bolster, and lateral motion rollers located within said pocket-like bearing member and bearing against said surface and the radial bearing member.

2. In combination, a truck bolster formed with a pocket, an upwardly spring pressed side bearing structure mounted within said pocket, a roller supported bearing element carried by said side bearing structure, a body bolster, a pocket-like bearing member located within the body bolster and serving to maintain said bearing element against displacement, and lateral motion rollers interposed between said bearing element and said pocket-like bearing member and located within the latter.

3. In combination, a truck bolster, a side bearing structure mounted therein, a roller supported bearing element carried by the side bearing structure movable laterally with respect to the truck bolster, a body bolster, a bearing member mounted within the body bolster and partially housing said bearing element, and lateral motion rollers mounted between said bearing element and said bearing member and enclosed within the latter.

4. In combination, a truck bolster, a side bearing member mounted therein, a roller supported bearing element mounted on said member and movable laterally with respect to the truck bolster, a body bolster, a bearing member of housing-like form mounted within the body bolster, and lateral motion rollers mounted between said bearing element and said last-named bearing member and enclosed and concealed within the latter, the confronting faces of the bearing element and bearing member and the rollers themselves being so shaped that relative movement of the body

and truck bolsters will be normally prevented.

5. In combination, a truck bolster, a side bearing structure mounted therein and including a roller supported bearing element movable laterally with respect to the truck bolster, a body bolster having an opening in its bottom, a bearing member of pocket-like form mounted within said opening in the body bolster, and lateral motion rollers mounted between said bearing element and said bearing member, and contained entirely within the latter.

6. The combination of a truck bolster having a pocket therein, a resiliently supported side bearing structure mounted in said pocket, a roller supported bearing element mounted on said structure movable transversely of the bolster, said bearing element extending into and being guided by the walls of the pocket, a body bolster, a bearing member mounted within the body bolster and receiving said bearing element, and lateral motion rollers mounted between said bearing member and said bearing element.

7. The combination of a truck bolster having a pocket therein having walls continued above the top, a side bearing structure mounted within the pocket and including a resiliently supported bearing element received partly between said walls, a roller mounted thereon, and a bearing element movably mounted on the roller and movable transversely of the bolster, a body bolster, a bearing member removably mounted within the body bolster, and rockable elements located between the bearing member and the second named bearing element and enclosed within the former.

8. The combination of a truck bolster, a side bearing structure mounted within the truck bolster and including a resiliently supported bearing element, a roller mounted thereon, and a bearing element movably mounted on the roller and movable transversely of the bolster, a body bolster, a bearing member located within the body bolster, and rockable elements located between the bearing member and the second named bearing element, said bearing member having attaching portions capable of attachment to the usual bottom plate of the body bolster.

9. The combination of a truck bolster having a pocket therein, a side bearing structure mounted within said pocket and including a lower bearing element, a bank of plate springs within the bottom of the pocket supporting said bearing element resiliently, a roller mounted upon the top of said bearing element, a bearing element resting upon the roller and movable laterally of the bolster, a body bolster, a bearing member of pocket-like formation fitting up within the body bolster, lateral motion rollers arranged between the pocket-like bearing member and

the second named bearing element, and means coacting with said lateral motion rollers normally maintaining the bolsters in neutral position.

- 6 10. The combination of a truck bolster having a pocket therein, a side bearing structure mounted within said pockets and including a lower bearing element, a bank of plate springs within the bottom of the pocket supporting said bearing element resiliently, a roller mounted upon the top of said bearing element, a bearing element resting upon the roller and movable laterally of the bolster, a body bolster, a bearing member of pocket-like formation fitting up within the body bolster, lateral motion rollers arranged between the pocket-like bearing member and the second named bearing element, and means coacting with said lateral motion rollers normally maintaining the bolsters in neutral position and restoring the bolsters to neutral position subsequent to relative movement.

11. In combination, a truck bolster formed 25 near each end with a pocket having end walls prolonged upwardly beyond the top of the bolster, a body bolster, a bearing member mounted within the lower portion of the body bolster, a side bearing assembly mounted 30 within the pocket and including a roller enclosed therewithin, the side bearing assembly further including a bearing member seated upon the roller and having portions located inwardly of said pocket walls, 35 and a plurality of rollers mounted upon said last named bearing member and located within the bearing member in the bolster.

12. In combination, a truck bolster formed near each end with a pocket having end walls 40 prolonged upwardly beyond the top of the bolster, a body bolster, a bearing member mounted within the lower portion of the body bolster, a side bearing assembly mounted within the pocket and including a roller enclosed therewithin, the side bearing assembly further including a bearing member seated upon the roller and having portions located inwardly of said pocket walls, a plurality 45 of rollers mounted upon said last named bearing member and located within the bearing member in the bolster, and thrust means between the outer end of the first named roller and the outer wall of the pocket.

In testimony whereof I affix my signature.

THOMAS H. SYMINGTON.
